SPRING HOLDING CLIP FOR USE IN RADIOS
AND OTHER DEVICES

Knut E. Birger Stenberg, Attleboro, Mass., assignor to Associated Attleboro Manufacturers, Inc., Attleboro, Mass., a corporation of Massachusetts

Application January 19, 1938, Serial No. 185,718

4 Claims. (Cl. 287—53)

My invention relates to spring holding clips for use in radios or other devices having rotatable rods for dial turning, tuning or other purposes to attach suitable turning knobs to the ends of such rods.

An object of my invention is to provide a novel type of turning clip which may be readily and cheaply stamped out in quantity for frictionally securing such a knob to such a rod without the necessity of separate screws or means thought necessary in former types of attaching devices.

These and such other objects of my invention as may hereinafter appear will be best understood from a description of the accompanying drawing which illustrates an embodiment thereof in use in attaching a turning knob to the end of a turning rod of a radio cabinet.

In the drawing,

Fig. 1 is a front elevation of a radio cabinet having the knobs of the turning rods attached thereto through the medium of my invention.

Fig. 2 is a vertical sectional view taken along the line 2—2 of Fig. 1.

Fig. 3 is a vertical sectional view showing my improved spring clip in the position it assumes prior to having its bowed portion flattened by the turning rod as shown in Fig. 2 in attaching said knob to said rod.

Fig. 4 is a rear elevational view of the clip in position on the knob as shown in Fig. 3.

Fig. 5 is a rear elevational view of the turning knob shown in Fig. 4 with my spring holding clip removed.

Fig. 6 is a perspective view of my improved spring holding clip.

In the drawing, wherein like characters of reference generally indicate like parts throughout, 10 generally indicates a spring holding clip constructed in accordance with my invention.

Said clip may be conveniently constructed by bending it of flat sheet metal in one or more punching, stamping or metal shaping or cutting operations. Said clip comprises a bowed longitudinally extending portion 12 and a portion 14

projecting radially outwardly from an end thereof having an integral lug 16 of substantial width projecting longitudinally in the same direction as said bowed portion from a portion thereof preferably substantially the center portion thereof

50 in my preferred embodiment. Said lug 16 preferably comprises a flat portion of substantial width struck up or otherwise formed from the flat metal of the radially extending portion 14 having the flat portion 18 projecting longitudinally 55 in the same general direction as said bowed por-

tion 12 and being struck up from the center portion 20 of said radially extending portion, leaving the cut out portion 22 therein.

To provide substantial resilient width to said lug, said lug preferably terminates in an end 24 bent substantially at right angles thereto in my preferred embodiment towards said longitudinally extending portion 12.

As stated, my improved spring holding clip is particularly adapted for use in radios or other devices having rotatable rods for setting dials, tuning or other purposes. I have therefore shown in Fig. 1 a radio cabinet 26 having the tuning dial 28 and tuning pointer 30 and rotatable rods 32 and 32' projecting forwardly from suitable holes in the front thereof. The rotatable rod 32 may be employed for the purpose of setting the pointer 30 or tuning, and the rod 32' may be provided for the volume control. Rod 32, shown in Fig. 2, is typical of such rods and is provided with a flat portion 34 at the outer end thereof for the attachment of the knob 36 thereto. The knob 36 is of generally solid cylindrical shape and may be provided with a knurled turning portion 38 at the outer end thereof.

In my preferred embodiment, for a purpose to be described and to permit the inner end of the knob 36 to rest in close proximity to the wall of the radio cabinet, said inner end is preferably provided with a central inset portion 40 generally of cylindrical shape and thus providing a wall 42 projecting axially inwardly from said knob externally of said inset portion. Said knob is provided with a central axial hole 44 extending from the inner end thereof and thus where the inset center portion 40 is employed from the outer end thereof. The outer end of said rod 32 may be round and provided with an axially extending segmental cut out portion forming the flat portion 34. In this instance, the axial hole 44 is also round. It is obvious however that both the end of the rod 32 and the axial hole 44 may be of any desired shape so long as sufficient clearance is provided to receive the longitudinally extending portion 12 of my improved clip 10, to compress the bow 46 thereof

from the curved position shown in Fig. 3 to the more flattened shape shown in Fig. 2 which bow thereafter tends to expand to its original position to urge the end of said rod against the opposite wall of said axial hole 44 to resiliently retain said knob 36 to the end of said rod 32. Said knob 36 is also provided with a hole 48 extending axially from the inner end of said knob and, if a central inset portion 40 be employed

from the outer end thereof, located radially of said central hole 44, which hole 48, while preferably cylindrical, may also be of any desired shape.

- 5 The axially or longitudinally extending lug 16 of my improved spring clip is spaced from the axially or longitudinally expanding bowed portion 12 a sufficient distance to project within said hole 48. The inner end of said lug 16 is preferably of a compressible size to be resiliently retained within said radial hole 48 and as stated, for this purpose the inner end thereof terminates in the flat portion 24 bent substantially at right angles thereto.
- 15 If a central inset portion 40 be provided, the outer end 50 of said radially projecting portion 14 may also resiliently abut the axially extending wall 42 of said knob exterior of said cut out portion. As resilient metal is employed the portion 20 of my improved spring holding clip 52 connecting the longitudinally bowed portion 12 and radially extending portion 14 is inherently somewhat curved and for this purpose if desired, as in the embodiment shown, the central inset knob 25 portion may be provided with a supplemental central inset portion 54 therein to accommodate said curve, and said central inset portion 40 may also be provided with a radially extending inset channel 56 to receive therein the radially outwardly projecting portion 14 of my improved spring clip.

If desired, to more evenly abut the flat end of the longitudinally extending portion of my spring clip 10, the axial hole 44 may be provided with a 35 flat portion 58 aligned with the radially extending channel 56 therein.

It is thus obvious that in use, it is merely necessary to align the axially extending portion 12 of my improved clip with the axial central plug hole 44 and the lug 16 with said radially spaced axial plug hole 48 and by simple axial pressure exerted on the radial portion 14 of said clip insert the longitudinally extending bowed portion 12 thereof within said axial hole 44 and compress said lug portion 16 within said axial hole 48. As the inturned end 24 of said lug portion 16 is inserted axially inwardly of the radial knob hole 48, the end 24 thereof bent substantially at right angles thereto, in the embodiment shown 50 slightly more than right angles, will project substantially diametrically across said hole 48 and abut a wall of said radial knob hole to force the opposite longitudinally extending portion 18 thereof against the opposite portion of the wall of said radial plug hole to resiliently confine said 55 knob 36 within said radial plug hole 48 to retain said clip 10 to said knob 36.

The knobs may be made up and sold as units with the spring clips attached as shown in Figs. 60 3 and 4. When it is desired to attach or detach the knob 36 to the end of the rod 32, it is obvious that it is merely necessary to align the bowed portion 12 of said spring clip with the flat portion 34 on the end of the rod and push the knob inwardly. When thus inserted the bowed portion 65 will become flattened from the position shown in Fig. 3 to the position shown in Fig. 2, by the flat end 60 thereof abutting the flat portion 58 of said hole 44 to urge said rod 32 against the opposite wall of the hole 44 to resiliently secure the knob 36 to the end of the rod 32. It is thus obvious that when the portion 12 of the spring clip 10 is inserted within the axial hole 44 that it will provide a resiliently expandable and 70 contractile socket with said hole 44 for resiliently

retaining the knob 36 to the end of said turning rod 32.

It is apparent that I provide a novel type of spring holding clip particularly adapted for use in holding knobs to rod ends with the advantages 5 explained above.

As shown in Fig. 2, the end 24 of the lug 16 in attached position is preferably at slightly less than a right angle to the longitudinally extending portion 18 to cause said end to bite into the 10 opposite side of the wall at an acute angle. It is thus obvious that it will be substantially impossible to pull the lug 16 out of its hole 48 for the more pressure exerted thereon for this purpose the more will said pressure cause said end 15 24 to bite into the wall of the hole 48 and lock said lug therein.

It is understood that my invention is not limited to the specific embodiment shown and that various deviations may be made therefrom without departing from the spirit and scope of the appended claims.

What I claim is:

1. A spring holding clip for use in radios or other devices having a rotatable rod having a flat 25 portion at the outer end thereof, and a knob member having a knurled turning portion at the outer end thereof, a central axial hole therein extending from the inner end thereof having a wall and a hole extending axially from the inner 30 end thereof located radially of said central hole, a flat metal spring clip comprising a radially inwardly bowed portion adapted to extend axially of the flat portion of said turning rod to have the flat end thereof abut the surface of said axial hole 35 to press the extended side wall thereof against said rod to confine said rod against the opposite wall of the central axial rod hole and a portion projecting integrally radially outwardly from the inner end thereof having an integral lug projecting axially inwardly from a portion thereof adapted to project axially inwardly within the radial knob hole of a width to engage the walls thereof to retain said spring clip to said knob and said knob to said rod.

2. A flat metal spring clip for use in attaching knobs to rotatable radio rods, comprising an outwardly bowed longitudinally extending portion and a portion projecting radially outwardly from an end thereof having an integral lug of substantial 50 width projecting longitudinally in the same direction as said bowed portion from a portion thereof.

3. A spring holding clip for use in radios or other devices having a rotatable rod having a flat 55 portion at the outer end thereof, and a knob member having a knurled turning portion at the outer end thereof, a central axial hole therein extending from the inner end thereof having a wall and a hole extending axially from the inner end 60 thereof located radially of said central hole, a flat metal spring clip comprising a radially inwardly bowed portion adapted to extend axially of the flat portion of said turning rod to have the flat end thereof abut the surface of said axial 65 hole to press the extended side wall thereof against said rod to confine said rod against the opposite wall of the central axial rod hole and a portion projecting integrally radially outwardly from the inner end thereof having an integral lug projecting axially inwardly from a portion thereof adapted to project axially inwardly within the radial knob hole terminating in an end bent at slightly less than right angles thereto, 70 projecting diametrically across said hole and 75

abutting a wall of said radial knob hole at an acute angle to positively lock the axially extending portion of said lug against the opposite wall of said plug hole against axial outward movement thereof to retain said clip to said knob and said knob to said rod.

4. A flat metal spring clip for use in attaching knobs to rotatable radio rods, comprising an

outwardly bowed longitudinally extending portion and a portion projecting radially outwardly from an end thereof having an integral lug projecting longitudinally in the same direction as said bowed portion from a portion thereof terminating in an end bent at slightly less than right angles thereto.
